UNITED STATES PATENT OFFICE.

ALFRED HEALD, OF PHILADELPHIA, PENNSYLVANIA, ASSIGNOR TO
McCALLUM, CREASE & SLOAN, OF SAME PLACE.

DESIGN FOR CARPET.

Specification forming part of Design No. 6,716, dated June 24, 1873; application filed June 6, 1873.

To all whom it may concern:

Be it known that I, ALFRED HEALD, of the city and county of Philadelphia, State of Pennsylvania, have invented a Design for a Carpet-Pattern, (D,) of which the following is a specification:

The figure in the accompanying drawing represents sufficient of a carpet-pattern to illustrate my design, which consists principally of two broad bands or ribbons, A and B, crossing each other at right angles, and arranged in the manner clearly represented in the drawing, so as to form square spaces within which are cruciform ornaments D, both the

latter and the said ribbons being ornamented in a manner so clearly shown in the drawing as to require no minute description.

Irrespective of the colors employed, I claim—

The design for a carpet-pattern, substantially as described, and as represented in and by the accompanying drawing.

In testimony whereof I have signed my name to this specification in the presence of two subscribing witnesses.

ALFRED HEALD.
